ABSTRACT

A mine roof support for use at a mineral face has a flushing screening shield arranged on its goaf side. The screening shield is in at least two parts one being an upper part and another a lower part, the parts being hingedly connected together by a hinge means having its axis lying in the longitudinal direction of the mineral face. The upper shield part is hingedly connected to the upper or roof-engaging structure of the support, preferably by a universal joint, and the lower shield part is hingedly connected to the base or lower part of the support by a hinge having its axis transverse to the longitudinal direction of the face. Thus, the screening shield is additionally pivotally movable laterally relatively to the support. In one preferred embodiment the axis of the hinge, connecting the lower screen part to the base or lower part of the screen, lies parallel to the floor of the mine and, when viewed from the longitudinal direction of the mineral face, is disposed approximately centrally of the support.

MINE ROOF SUPPORT

BACKGROUND OF THE INVENTION

The invention is concerned with a mine roof support a support frame and more particularly but not essentially to a mine roof support with a multi-part flushing screening shield, the parts of which are mutually connected through hinges with hinge axes lying in the longitudinal direction of the face, and the upper and lower parts of which are connected with a roof bar construction and a base plate of the support, wherein the connection with the roof bar construction at least is formed hingedly about a hinge axis lying transversely to the longitudinal direction of the face.

A support of the above-mentioned kind is described in U.S. Pat. No. 3,483,705. In the known support there is provided between the upper part of the flushing screening shield and the roof bar construction a hinged connection which is also pivotable about an axis lying parallel to the longitudinal direction of the face, but with some freedom of vertical movement. This results in that the upper part of the flushing screen has the possible freedom of movement so that it can be adapted to all circumstances. With the construction specified such an adaptation can however only occur between the upper part of the flushing screen and the roof bar construction. Because of the hinged connection to the under part of the flushing screen the upper part meanwhile is hindered from certain adaptation movements. It is a question herein particularly of adaptation movements which are requisite in the movements parallel to the stratification between roof and floor in the longitudinal direction of the face, in which the roof bar construction moves outward laterally from the position normal to the stratification over the base plate. The same difficulties arise when the base plate inclines laterally because of the irregularities of the floor. Because of this deficiency in adaptability large loading peaks occur in the hinges of the flushing screen which can damage these hinges. Deformations also occur in the flushing screen itself. In addition on inclination of the props in the longitudinal direction of the face, the props of the support can impinge on the solid parts of the flushing screen so that there can also result jamming or deformations of these parts.

It is therefore an object of the invention to improve a mine roof support in such a way that the parts of the flushing screen shield and especially the hinge axes lying in the longitudinal direction of the face are protected from overloading and deformations, which can occur when the base plate is inclined laterally because of irregularities of the floor or when movements parallel to the stratification between roof and floor occur in the longitudinal direction of the face.

SUMMARY OF THE INVENTION.

According to the present invention there is provided a mine roof support, for use at a mineral face comprising a base member, extensible prop means mounted on said base member, a roof-engaging structure mounted on said prop means for application thereby to a roof to be supported, a screening shield arranged on the goaf side of the support and consisting of at least two shield elements, at least one hinge connecting said shield elements one to the other, the axis of said hinge lying in the longitudinal direction of the mineral face, and means connecting the screening shield to upper and

lower parts of the support, said connecting means providing for additional movement laterally of the screening shield relatively to the support.

More specifically there is provided a mine roof support as described in the preceding paragraph having a multi-part flushing screen shield arranged on the goaf side of the support, hinge means mutually connecting the parts of said screening shield and having their axes lying in the longitudinal direction of the face; hinge means connecting the upper part of the shield to the roof-engaging structure and having its hinge axis lying transversely to the longitudinal direction of the mineral face, and hinge means connecting the lower part of the shield with the base member and having a hinge axis 10 which is parallel to the floor of the mine and transversely to the longitudinal direction of the face and which, viewed from the longitudinal direction of the face is disposed approximately centrally of the support, whereby the screening shield is pivotally movable not only in the direction of length of the support but additionally laterally relatively thereto.

As a result of the hinged connection in these supports between the flushing screen and the base plate of the support no transverse forces can be induced in the hinge mechanism of the flushing screen in the tilt position of the base plate or in movements parallel to the stratification between roof and floor in the longitudinal direction of the face, so that deformations or damages effected through these forces are avoided. Since the 20 flushing screen can tilt with the props in movements parallel to the stratification in the longitudinal section of the face impact of the props on the side part of the flushing screen is no longer possible.

In order, after inclination of the flushing screen together with the support, to be able to align it again into the normal position relative to the underpart of the support, aligning devices are arranged between the props of the support on the one hand and the base plate or parts associated with the base plate on the other hand 30 which serve for swivelling of the flushing screen about the hinge between the base plate and the underpart of the flushing screen. These aligning devices suitably have resilient restoring elements. Alternatively the aligning devices can also have pressure-medium cylinders 40 which serve for application of the aligning forces.

BRIEF DESCRIPTION OF THE DRAWINGS

One embodiment of the invention by way of example is described below with reference to the drawing in 50 which is illustrated a support frame according to the invention in side view and partial section.

DESCRIPTION OF THE PREFERRED EMBODIMENTS

55 The support illustrated in the drawing has a base plate which is indicated by reference numeral 1. On this base plate 1 are arranged several props 2 which mutually support a roof bar construction 3. The displacement of the props 2 on the base plate 1 and on the roof bar construction 3 is flexible all round. For alignment of the props 2 aligning devices 4 are arranged on the base plate 1, which devices serve for alignment of the props 2 relative to the base plate 1. Furthermore the base plate 1 is provided with a ram 5 the reciprocatable piston rod of which acts on a face conveyor 6.

On the goaf side of the support there is provided a flushing screen which is indicated generally by refer-

ence numeral 7. The flushing screen 7 consists of two box elements 7a and 7b which are open towards the coal face and embrace with their side walls the rearward props 2 of the support on the flanks. The lower box element 7a is connected through hinge pins 8 with the base plate 1. The hinge pins 8 lie on a joint axis which lies parallel to the floor and transversely to the longitudinal direction of the face and seen from the longitudinal direction of the face, is disposed approximately centrally in the support. The upper box element 7b is hingedly connected, universally movable, to the roof bar construction 3 by means of a chain 9 or like connecting means. Furthermore the box elements 7a and 7b are mutually connected by guide rods 10 which hingedly engage on the side wall of the lower box element 7a and in the region of the rear wall of the upper box element 7b. The hinge axes extending through the engagement points of the guide rods 10 lie in the longitudinal direction of the face.

As can be seen from the drawing the flushing screen shield is movable towards the support in a plane perpendicular to the floor and in the longitudinal direction of the face. Because of this the flushing screen 7 with its hinges lying in the longitudinal direction of the face no longer prevents inclination of the base plate in the longitudinal direction of the face. Also in movements parallel to the stratification between roof and floor in the longitudinal direction of the face the flushing screen can tilt correspondingly without its hinges being overloaded or that impact of the props on the side walls of the screen elements 7a and 7b needs to be feared.

In place of the hinge pins 8, used in the example, obviously other connecting means between the lower screen element and the base plate 1 can be arranged, which permit movement of the flushing screen shield 7 relative to the base plate 1 in the plane lying in the longitudinal direction of the face and vertically to the floor. For this purpose mortise-and-tenon joints with longitudinal holes can be used, which are arranged, for example on both sides of the base plate. Likewise there can also be used as connecting means quadrilateral links or the like, the hinge axes which lie parallel to the

floor and transversely to the longitudinal direction of the face. Similar connecting means can also be arranged between the upper screen element 7b and the roof bar construction 3.

5 We claim:

1. A mine roof support, for use at a mineral face, comprising a base member, extensible prop means mounted on said base member, a roof-engaging structure mounted on said prop means for application thereby to a roof to be supported, a multi-part flushing screen shield including upper and lower parts arranged on the goaf side of the support, first hinge means mutually connecting the parts of said screening shield and having their axes lying in the longitudinal direction of the mineral face, a flexible member connecting the upper part of the shield and the roof-engaging structure and which permits movements of the upper part of the shield about an axis lying transversely to the longitudinal direction of the mineral face, and second hinge means connecting the lower part of the shield with the base member and having a hinge axis which lies transversely to the longitudinal direction of the mineral face, whereby the screening shield is pivotally movable with respect to the support not only toward and away from the mineral face but also parallel thereto.

2. A support according to claim 1 wherein aligning devices are arranged between props of the support on the one hand and the base member or the parts connected with the base member on the other hand.

3. A roof support as claimed in claim 1, wherein said flexible member connecting the upper part of the shield and the roof-engaging structure is a universal hinge or joint.

4. A roof support as claimed in claim 1, wherein the hinge axis of said second hinge means when viewed from the mineral face is disposed approximately centrally of the support.

5. A roof support as claimed in claim 4 wherein the hinge axis of said second hinge means is parallel to the floor of the mine.
